UNITED STATES PATENT OFFICE.

JOHN G. STITES, OF WILLOWBROOK, AND FRANK STITES, OF LOS ANGELES, CALIFORNIA.

FLYING-MACHINE SUPPORTING-PLANE.

965,491.

Specification of Letters Patent. Patented July 26, 1910.

Application filed March 24, 1910. Serial No. 551,312.

To all whom it may concern:

Be it known that we, JOHN G. STITES and FRANK STITES, citizens of the United States, residing at Willowbrook, California, and 5 Los Angeles, California, respectively, have invented a new and useful Flying-Machine Supporting-Plane, of which the following is a specification.

Our object is to construct an improved 10 supporting plane to be used either in mono-plane or bi-plane flying machines, and our invention consists of the novel features herein shown, described and claimed.

In the drawings: Figure 1 is a top plan 15 view of a flying machine supporting plane embodying the principles of our invention. Fig. 2 is a front elevation of a bi-plane construction as seen looking in the direction indicated by the arrow 2 in Figs. 1 and 3. 20 Fig. 3 is a side elevation as seen looking in the direction indicated by the arrow 3 in Figs. 1 and 2. Fig. 4 is an enlarged fragmental plan showing the details of construction. Fig. 5 is a cross section on the line 25 5—5 of Fig. 4.

Referring to the drawings in detail the flying machine supporting planes 1 and 2 are or may be exact duplicates and the details of construction are shown in Figs. 1, 4 30 and 5. The supporting planes are preferably three times as large crosswise of the line of travel as they are lengthwise of the line of travel and for a small machine they would be about eight feet by twenty-four 35 feet in plan. The rafters 3 and 4 are set parallel about six feet apart and the ridge pole is intermediate of the rafters and parallel therewith. The canvas consists of a sheet 6 large enough to cover the entire area 40 of the plane and pockets 7, 8 and 9 are formed by sewing strips under the canvas in positions to receive the rafters 3 and 4 and the ridge pole 5, and pockets 10 are formed by sewing strips on top of the canvas 45 crosswise of the pockets 7, 8 and 9 to the ridge pole 11 and 12. The rafter 3 is set at the extreme edge of the proposed plane, the ridge pole 5 is set about two feet from the rafter 3, and the rafter 4 is set about four feet from the ridge pole. After the timbers constituting the rafters 3 and 4, the ridge pole 5 and the ribs 11 and 12 have

been inserted into the pockets of the canvas they may be nailed together by nailing through the canvas, or openings may be 55 made for the insertion of the nails to suit the fancy of the constructor. Gables 13 are inserted at each side of the plane, that is, crosswise of the ends of the ridge pole and rafters so as to hold the ridge pole 5 the 60 desired height above the level of the rafters 3 and 4, and in an eight by twenty-four foot plane, the ridge pole 5 will be elevated about four or six inches. Any desired form of truss rods and braces may be employed to 65 strengthen the plane thus constructed.

In Fig. 2 posts 14 and 15 are inserted vertically near the center running line to carry the power mechanism et cetera and posts 16 and 17 are inserted at the ends of 70 the rafters and ridge poles, and posts 18 and 19 are inserted half way between the center posts and the end posts. The distance between the planes may be varied to suit.

Heretofore constructors of flying machine 75 supporting planes have gone to a great deal of trouble and expense to make the planes of various curvatures in cross section to suit their ideas of efficiency et cetera, but we have found from actual experience that a 80 plane consisting of two flat surfaces sloping each way from a ridge pole as we have shown and described possesses every element of efficiency required in a flying machine.

We claim:

1. A flying machine supporting plane comprising a canvas having side and intermediate longitudinal and transverse pockets, rafters inserted into the side longitudinal pockets, a ridge pole inserted into the intermediate longitudinal pocket and ribs inserted into the transverse pockets and secured to the ridge pole and rafters, said ridge pole being above the level of the rafters so as to form an angular plane, the 95 angle extending transverse of the line of travel.

2. A flying machine supporting plane comprising two substantially parallel planes mounted one above the other, each plane 100 comprising a canvas having side and intermediate longitudinal and transverse pockets, rafters inserted into the side longitudinal pockets, a ridge pole inserted into the inter-

mediate longitudinal pocket and ribs inserted into the transverse pockets and secured to the ridge pole and rafters, said ridge pole being above the level of the rafters so as to form an angular plane, the angle extending transverse of the line of travel, said planes being connected together by

posts inserted vertically at the ends of the rafters and at the ends of the ridge poles.

JOHN G. STITES.
